Albert Weewetzer, Elgin, Ill., assignor to Illinois
Watch Case Company, Elgin, Ill., a corporation
of Illinois

Application November 20, 1937, Serial No. 73,078

Term of patent 3½ years

To all whom it may concern:

Be it known that I, Albert Weewetzer, a citizen of the United States, residing at Elgin, in the county of Kane and State of Illinois, have invented a new, original, and ornamental Design for a Vanity Case, of which the following is a specification, reference being had to the accompanying drawing, forming part thereof, in which—

Figure 1 is a plan view;

Fig. 2 is an end elevation; and

Fig. 3 is a side elevation of the vanity case showing my new design.

The characteristic feature of the instant design resides in the reversely curved and oppositely tapering top edge portion of the relatively thin vanity case having oppositely tapering side edge portions and inwardly curved upper and lower edge portions which merge with one side of said case.

I claim:

The ornamental design for a vanity case, as shown and described.

ALBERT WEWETZER.
